ROCKET GUN

Irwin R. Barr, Kingsville, Joseph N. Bond, Baltimore, Bertram W. Gore, Jr., Owings Mills, and Nicholas J. La Costa, Kingsville, Md., assignors to Aircraft Armaments, Inc., Baltimore, Md., a corporation of Ohio

Filed Apr. 28, 1953, Ser. No. 351,667
8 Claims. (Cl. 89—1.7)

This invention relates in general to automatic guns and more particularly to an automatic rocket gun specially adapted for use in tank turrets and the like.

An object of this invention is to provide a rocket gun having means for utilizing the recoil or jet blast of the rocket when fired to effect automatic gun operation. A buffer piston is arranged to absorb energy from the rocket blast and thereby load a double acting spring for effecting axial movement of a firing tube wherein movement of the firing tube actuates a loading mechanism for re-loading the gun and allowing continuous automatic operation.

Another object of this invention is to provide an automatic rocket gun having a closed breech which traps the rocket blast to increase the effective firing range of the gun and prevent the uncontrolled escape of hot gases rearwardly thereof.

Another object of this invention is to provide an automatic rocket gun having a high rate of fire.

Still another object of this invention is to provide an automatic rocket gun which is dependable in operation and which is relatively small as compared with other automatic weapons for the size round being launched.

Further and other objects will become apparent from a reading of the following detail description when taken in combination with the accompanying drawing wherein like numerals refer to like parts.

In the drawing:

FIGURE 1 is a fragmentary side elevation view of the rocket gun of this invention.

FIGURE 2 is a sectional view taken on line 2—2 of FIGURE 1.

FIGURE 3 is a sectional view taken on line 3—3 of FIGURE 1.

FIGURE 4 is a sectional view taken on line 4—4 of FIGURE 1.

Referring to the drawing, the rocket gun includes a generally cylindrical housing 1 having a bore 2 formed therein for telescopically receiving an open-ended firing tube 3. The rearward end 4 of firing tube 3 as best shown in FIGURE 2 is increased in wall thickness for closely engaging the inner wall or bore 2 of housing 1. A pair of firing tube support bearings 5 and 6 are rigidly secured to the inner wall of housing 1 at its forward end 7 for slidably engaging the firing tube and permitting only axial movement thereof in cooperation with the increased wall thickness portion at the rearward end of the tube.

A piston chamber 8 formed at the rearward end of housing 1 in coaxial alignment with firing tube 3 and having a greater diameter than the bore of the housing is arranged to slidably receive a piston 9 and allow limited axial movement thereof from a forward position shown in FIGURE 2 abutting the rearward end 4 of tube 3 to a rearward position abutting a transverse bulkhead 13 carried by housing 1. An opening 94 formed in bulkhead 13 vents the piston chamber to atmosphere. A buffer piston 10 rigidly connects with piston 9 through an extension member 11 to form a piston assembly. Buffer piston 10 is slidably received within a fluid-filled shock absorbing cylinder 12 carried by bulkhead 13. The fluid in cylinder 12 is pressurized by means such as conventional hydraulic accumulator 14 connecting with the cylinder through tube 15. The pressurized fluid acting against buffer piston 10 urges the buffer piston and piston

2

9 into the forwardmost position. Forces applied to piston 9 from within firing tube 3 will be absorbed by the pressurized fluid and cause axial recoil movement of the piston assembly in a rearward direction.

5 A pair of radially extending brackets 16 and 17, rigidly secured to firing tube 3 adjacent its forward end 18, connects with a pair of piston rods 19 and 20. Piston rods 19 and 20 extend generally parallel to housing 1 and axially into a pair of tubular guides 21 and 22, respectively. Guides 21 and 22 are rigidly secured to housing 1 on either side thereof as shown in FIGURES 1 and 2. The free ends 23 and 24 of rods 19 and 20 carry pistons 25 and 26 which slidably engage the inner walls of guides 21 and 22. A pair of double acting preloaded springs 27 and 28 are carried within guides 21 and 22 and concentrically arranged relative to rods 19 and 20 adjacent the forward ends thereof. Pistons 29 and 30, having tubular extension members 31 and 32 rigidly secured thereto, are concentrically arranged relative to rods 19 and 20 so as to engage the forward end of the associated double acting spring 27 or 28. The length of extensions 31 and 32 is such that when the firing tube is in the neutral position shown in FIGURE 2 no spring pressure is exerted but any rearward movement beyond 20 that neutral position compresses the spring and urges the firing tube forward. A pair of pistons 33 and 34 concentrically arranged relative to rods 19 and 20 engage the rearward end of double acting springs 27 and 28 so that when firing tube 3 moves forwardly, pistons 25 and 26 carried by rods 19 and 20 will cause axial movement of pistons 33 and 34 to compress springs 27 and 28 and effect return motion of the firing tube back to the neutral position.

An automatic loading mechanism responsive to axial movement of the firing tube is employed which includes actuating pistons 35 and 36 carried within guides 21 and 22 and rearwardly of double acting springs 27 and 28 so that axial movement of firing tube 3 causes pistons 25 and 26 to engage the actuating pistons and effect forward movement thereof with the firing tube within the limits defined by slots 37 formed in each guide 21 and 22. An actuating return spring 38 is provided within each guide 21 and 22 so that it acts between piston 35 or 36 and piston 33 or 34 whereby pistons 35 and 36 are normally urged in the rearwardmost position relative to slots 37 as shown in FIGURES 1 and 2. An annular extension 39 secured to each piston 33 and 34 extends rearwardly within each guide 21 and 22 whereby movement of pistons 25 and 26, as a result of axial movement of the firing tube, causes the actuating pistons to move forwardly against the action of springs 38 and engage extension members 39. Continued forward movement of the firing tube then results in compressing double acting springs 27 and 28 to effect the desired return motion. Pins 40 secured to actuating pistons 35 and 36 extend through slots 37 for engaging one arm 41 of a bell crank 42, one on either side of housing 1, through an L-slot 43. Bell crank 42 is pivotally carried by pin 44 secured to wall 45 of an ammunition guide chute 55 secured to housing 1. The other arm 46 of bell crank 42 is provided with a slot 47 engaging a pin 48 secured to round charger 49, one on either side of housing 1, as best shown in FIGURE 3. Round chargers 49 each include a guide block 50 which pivotally carries a pawl 51 through pin 52. Pawl 51 is suitably urged so as to project into the feed path of the ammunition and engage the underside of a rocket round 53. Guide block 50 is slidably carried within a hollow box-like fairing 54 formed in wall 45 of ammunition guide chute 55. A slot 56 formed in box-like fairing 54 limits the movement of round charger 49 from the position shown in FIGURE 3 to a raised position wherein rocket round 53 is placed in coaxial align-

ment with firing tube 3. By rotating bell cranks 42, through linear movement of pistons 35 and 36, round chargers 49 are actuated to load the gun.

A second pair of round chargers 57, spaced from round chargers 49, are carried by wall 45, one on either side of ammunition guide chute 55 in the same manner that round chargers 49 are carried, whereby positive four point support for each rocket round is provided when loading the gun. Round chargers 57 are each actuated by a second bell crank 58 pivotally carried through pin 59 secured to wall 45 of guide 55. One arm 60 of bell crank 58 pivotally connects with a lever 61, pivotally secured to arm 41 of bell crank 42 through pin 62, so that rotation of bell crank 42 causes corresponding rotation of bell crank 58 to actuate all round chargers simultaneously and move a rocket into coaxial alignment with the firing tube.

As shown in FIGURE 1, a release sear 63 is pivotally carried by piston 9 through pin 64 for engaging notch 65 formed in firing tube 3 whereby the firing tube may be releasably secured to the piston. A spring loaded pawl 66, pivotally carried by shaft 64, is arranged to engage projection 67 formed on sear 63 so that counterclockwise movement of the pawl, as viewed in FIGURE 1, will disengage the sear and release firing tube 3 while clockwise movement of pawl 66 will not affect sear operation. To maintain pawl 66 in a generally upwardly projecting position abutting projection 67 and for urging sear 63 into engagement with firing tube notch 65, suitable spring means 68 may be employed. A cut-out 69 formed in the wall of piston chamber 8 provides space for unobstructed axial movement of piston 9 and its associated sear mechanism with the exception of a projection 70 formed on the inner wall of cut-out 69 which is arranged to engage pawl 66 when piston 9 is moved axially rearwardly a sufficient distance, whereby the sear mechanism is unlocked allowing free forward movement of the firing tube relative to the piston.

A snubber arrangement carried by housing 1 within fairing 76 is adapted to hold firing tube 3 in the neutral position and relieve sear 63 from shock loads developed by firing tube movement each time the gun fires. As shown in FIGURE 1, the snubber arrangement includes a pawl 77 carried by pin 78 for pivotal movement from the locking position wherein the pawl is in engagement with notch 79 formed in firing tube 3, to the unlocked position shown in dotted lines wherein the pawl is disengaged from notch 79. A spring 80 acting between housing 1 and pawl 77 urges the latter into positive engagement with notch 79. Automatic locking and unlocking of pawl 77 is effected by a latch 81 pivotally carried by pin 82 and spring urged in a counterclockwise direction as viewed in FIGURE 1, by means of spring 83. Actuation of latch 81 is effected through an extension 88 which is urged to an extreme position relative to the latch by spring 86 so that only those forces applied to extension 88 in a rearward direction are effective to rotate the latch. When the barrel is moved rearwardly from the neutral position shown in FIGURE 1 due to forces applied to piston 9, the firing tube is automatically unlocked as pawl 77 rides up on a cam 84 causing the latch to engage the tip end 87 of pawl 77 and hold it in the unlocked position. When the snubber arrangement unlocks the firing tube, the latter is free to move forwardly relative to the housing, following release of sear 63. As the firing tube moves forwardly, a projection 85 on tube 3 engages extension 88 and applies a force thereon in the forward direction which is ineffective to actuate latch 81 and the snubber arrangement therefore remains in the unlocked position. When the firing tube returns toward the neutral position from a forwardly extended position, a groove 91 formed in firing tube 3 provides the necessary clearance for extension 88 so that rotation of latch 81 will not be effected until the extension strikes projection 85. As the firing tube moves axially

rearwardly a short distance beyond the neutral position against the action of piston 9 due to the firing tube momentum, projection 85 strikes extension 88 and causes rotation of latch 81 which allows pawl 77 to swing into locked engagement with notch 79 on the firing tube. The slight rearward movement of firing tube 3 beyond the neutral position, due to its own momentum, is insufficient to effect actuation of sear 63 which is actuated only when a rocket round is fired.

The gun employs an electrical triggering system as shown in FIGURES 1 and 4. A rod conductor 74 extending through housing 1 as shown in FIGURE 4 connects with a switch 92, shown in FIGURE 1. Switch 92 is mounted on fairing 76 and is provided with an actuating rod 93 extending through an opening 94 in the housing so as to engage pawl 77. When pawl 77 is in the locked position engaging notch 79, switch 92 is closed, electrically connecting a suitable source of electrical potential such as a battery (not shown) with rod conductor 74 through lead 75. A manually controlled switch (not shown) may be employed in the circuit in addition to switch 92 for turning the trigger system off and on. A spring loaded contact element 71 carried by firing tube 3 engages rod conductor 74 and a conducting ring 72 on rocket 73 simultaneously when the firing tube is in the neutral position, completing a circuit when switch 92 is closed which fires the rocket. When pawl 77 is in the unlocked position, switch 92 is open, preventing operation of the triggering system to fire a rocket.

As shown in FIGURE 3, ammunition guide chute 55 connects with the underside of housing 1 to provide an opening 89 through which the rockets may be raised from the chute into coaxial alignment with the firing tube when the latter is near its forwardly extended position.

As shown in FIGURE 4, a link chute 90 communicating with guide chute 55 provides a path for disposing of conventional rocket connecting links (not shown) as they are removed from each rocket immediately before the rocket is positioned within the gun.

The normal operation of the gun can best be understood by describing a complete cycle beginning with the firing tube in the neutral position shown in FIGURES 1 and 2. At this time, a rocket round 72 is located within the firing tube abutting piston 9. The release sear 63 is in the locked position securing the firing tube relative to piston 9 so that the firing tube will move with the piston. Pawl 77 of the snubber assembly is in engagement with notch 79 on the firing tube preventing forward movement thereof relative to housing 1. When a voltage is applied through switch 92 and lead 75, an electrical circuit is completed, igniting rocket 73.

As the rocket leaves the firing tube, its exhaust reacts against piston 9 causing axial rearward movement thereof against the action of the pressurized fluid in cylinder 12. The rearward movement of piston 9 and firing tube 3 causes the snubber assembly to be actuated through cam 84 and projection 85 to unlock the firing tube, open switch 92, and permit forward movement thereof beyond the neutral position. The rearward travel of piston 9 and firing tube 3, due to reaction forces produced by firing the rocket, also positions pawl 66 rearwardly of projection 70 formed on the inner wall of cut-out 69. Then, as piston 9 moves forwardly due to the pressurized fluid in cylinder 12, pawl 66 engages projection 70 causing rotation of sear 63 to unlock the firing tube from piston 9. Since rearward movement of the firing tube, relative to its neutral position shown in FIGURES 1 and 2, compresses double acting springs 27 and 28, energy is imparted to the tube causing it to move forwardly with considerable force. Near the end of the forward travel of the firing tube, pistons 25 and 26 engage actuating pistons 35 and 36 causing movement thereof within guides 21 and 22 to rotate bell cranks 42 and 58 and position another rocket round within the gun housing

in coaxial alignment with the firing tube. Forward movement of firing tube 3, while actuation of the loading mechanism is being effected, also compresses double acting springs 27 and 28 to produce a rebound force for returning the firing tube to the neutral position shown in the drawing. As the firing tube strikes piston 9 on its return stroke, sear 63 engages notch 65 and the energy imparted to the piston by the moving tube causes slight rearward movement which is only sufficient to disengage the snubber latch 81 and allow pawl 77 to engage notch 79 so as to absorb the stresses which would otherwise be applied to sear 63.

When pawl 77 moves into engagement with notch 79, switch 92 is actuated to again complete an electrical circuit firing the new rocket round. The gun operates as previously described in connection with firing the first rocket round to load still another rocket. Continuous operation in this manner will continue until the source of electrical potential is disconnected from the switching circuit, at which time the firing tube will lock in the neutral position and the gun will be loaded.

By simply connecting the source of electrical potential so as to complete a circuit to the rocket, gun operation may again be effected. The firing rate of the gun, which is proportional to the average velocity of the moving firing tube, may be regulated by controlling the pressure of the fluid in cylinder 12. For example, if the pressure of the fluid is lowered, the ring tube will move rearwardly from the neutral position a greater distance which compresses the double acting springs more to increase the average velocity of the moving firing tube; whereas, if the pressure of the fluid is increased the double acting springs will be compressed less and the average velocity of the firing tube will be lowered.

The firing rate of the gun also may be increased over the firing rate under normal operation by eliminating switch 92 and providing electrical energy to the trigger system when the firing tube passes the neutral position from the forwardly extended position rather than after the firing tube is decelerated by piston 9 and locked in the neutral position by pawl 77. By applying electrical energy to the gun in this manner for increasing the rate of fire, the snubber assembly becomes effective only when stopping the gun and somewhat smoother operation therefore results because the firing tube moves from one extreme position to the other, never stopping at the neutral position when firing a new rocket round.

Though the gun is described in connection with firing rockets, it is merely by way of example and may obviously be readily adapted for use with any type of projectile.

Though a specific embodiment of the gun has been shown and described, it is to be understood that certain alterations, modifications and substitutions may be made without departing from the spirit and scope of the invention as defined by the appended claims.

We claim:

1. A closed breech automatic rocket gun comprising, a housing having a generally cylindrical bore formed therein, a piston slidably carried within said cylindrical bore adjacent one end thereof, a firing tube telescopically received within said bore, said tube being adapted for axial movement relative to said housing between a recoil position abutting said piston to a loading position spaced from said piston, double acting spring means urging said tube into an intermediate axial position, electrical means responsive to axial movement of said tube for firing said gun, hydraulic shock absorbing means communicating with said piston and allowing limited axial recoil movement thereof in response to firing said gun, and latch means releasably connecting said firing tube to said piston means carried by said housing and being responsive to axial movement of said tube independent of said piston for loading said gun.

2. An automatic gun comprising, a housing having a bore formed therein, a firing tube telescopically received

within said bore for axial movement relative to said housing, a piston slidably carried within said housing and communicating with said bore, spring means urging said piston in one extreme position for engaging said tube and absorbing energy released by firing said gun, releasable latch means connecting said piston with said firing tube whereby the firing tube is caused to move with the piston, said latch means being responsive to piston recoil movement for automatically releasing said firing tube and allowing axial movement thereof away from said piston, spring means carried by said housing and connecting with said tube for urging the latter into an intermediate position and causing cyclical movement thereof between a recoil position adjacent said piston and a loading position spaced from said piston, link means connecting with said tube and responsive to axial movement of said tube independent of said piston for loading said gun, and electrical means responsive to axial movement of said tube for firing said gun.

3. A automatic rocket gun comprising, a generally cylindrical housing, a shock absorbing piston slidably carried within said housing adjacent the rearward end thereof and arranged for limited axial movement relative to the housing, fluid means urging said piston into a forwardmost position, an open-ended firing tube telescopically received within said housing and arranged for axial movement relative thereto from a rearwardmost position abutting said piston to a forward position spaced from said piston, double acting spring means connecting with said firing tube for urging the same into an intermediate axial position, link means connecting with said firing tube and responsive to axial movement of said firing tube independent of said piston for loading said gun, and means responsive to the axial movement of said firing tube for firing said gun whereby energy imparted to said firing tube by said piston is absorbed by said spring means to effect continuous automatic operation.

4. An automatic rocket gun comprising, an open-ended firing tube, a housing supportingly receiving said tube and allowing axial movement thereof, a piston slidably carried within said housing in generally coaxial alignment with said tube, shock absorbing means urging said piston towards said tube for absorbing energy released by firing said gun, double acting spring means carried by said housing and connecting with said tube and responsive to said shock absorbing means for causing cyclical movement of the tube between a rearwardmost recoil position abutting said piston and a loading position spaced from said piston forwardly of the firing position, and link means connecting with said tube and responsive to the axial movement of said tube independent of said piston for automatically loading said gun.

5. An automatic gun comprising, an open-ended firing tube, a housing supportingly receiving said tube and allowing axial movement thereof, a piston slidably carried within said housing in generally coaxial alignment with said tube, recoil means urging said piston towards said tube and responsive to firing said gun for absorbing energy released thereby, actuating means carried by said housing and responsive to said recoil means for causing cyclical movement of the tube to either side of an intermediate firing position abutting said piston, link means connecting with said tube and responsive to the forward axial movement of said tube for automatically moving a round of ammunition into axial alignment with said tube, and means carried by said housing for firing said gun.

6. An automatic gun comprising, an open-ended firing tube, a housing having an opening for telescopically receiving said tube and allowing axial movement thereof, a piston slidably carried within said housing in generally coaxial alignment with said tube, recoil means urging said piston towards said tube and allowing axial recoil movement thereof for absorbing energy released by firing said gun, double acting spring means carried by said housing and urging said firing tube into an intermediate

position for causing cyclical movement of said firing tube between a rearwardmost recoil position abutting said piston and a loading position spaced from said piston forwardly of the firing position, latch means carried by said piston and engaging said firing tube whereby axial recoil movement of said piston causes like movement of said tube for compressing said double acting spring means, said latch means being responsive to axial forward movement of said piston for releasing said firing tube, lock means carried by said housing and releasably engaging said firing tube for transmitting shock loads to said housing and relieving said latch means, said lock means being responsive to relative axial rearward movement of said firing tube for releasing the latter and allowing free forward movement thereof, means responsive to axial movement of said tube independent of said piston and relative to said housing for automatically loading said gun, and means responsive to said lock means for firing said gun and effecting automatic operation.

7. An automatic rocket gun comprising, an open-ended firing tube, a housing having an opening for telescopically receiving said tube and allowing axial movement thereof, a piston slidably carried within said housing in generally coaxial alignment with said tube, spring means urging said piston towards said tube and allowing axial recoil movement thereof for absorbing energy released by firing said gun, double acting spring means carried by said housing and connecting with said firing tube for causing cyclical movement of the firing tube between a rearwardmost recoil position abutting said piston and a forward loading position spaced from said piston, latch means carried by said piston and engaging said firing tube whereby axial recoil movement of said piston causes like movement of said tube for compressing said double acting spring means, said latch means being responsive to axial forward movement of said piston for releasing said firing tube and allowing free forward movement thereof, means responsive to said free forward movement of said tube relative to said housing for automatically loading said gun, and means responsive to axial movement of

10 said tube relative to said housing for automatically firing said gun.

8. An automatic gun comprising, an open-ended firing tube, a housing having an opening for telescopically receiving said tube and allowing axial movement thereof, a piston slidably carried within said housing in generally coaxial alignment with said tube, spring means urging said piston towards said tube and allowing axial recoil movement thereof for absorbing energy released by firing said gun, a second spring means carried by said housing and connecting with said firing tube for causing cyclical movement of the firing tube between a recoil position abutting said piston at a location rearwardly of the firing position and a loading position spaced from the piston at a location forwardly of the firing position, latch means carried by said piston and engaging said firing tube whereby axial recoil movement of said piston causes like movement of said tube for compressing said second spring means, said latch means being responsive to axial forward movement of said piston for releasing said firing tube and allowing free forward movement thereof, means responsive to said free forward movement of said tube relative to said housing for automatically loading said gun, and means responsive to axial movement of said tube relative to said housing for automatically firing said gun.
